[57] **CLAIM**

An ornamental design for a theater-box toy for making changeable three-dimensional images, as shown and described.

DESCRIPTION

FIG. 1 is a perspective view of the theater-box toy for making changeable three-dimensional images, in an assembled configuration;

FIG. 2 is a front elevational view of the theater box toy for making changeable three-dimensional images showing my new design;

FIG. 3 is a side elevational view, the two sides of the toy being symmetrical;

FIG. 4 is a back elevational view;

FIG. 5 is a top plan view;

FIG. 6 is a bottom plan view; and,

FIG. 7 is a perspective view showing assembly of plates for insertion into the theater-box of the toy.

The broken lines forming geometric designs on the rectangular plates (e.g., FIGS. 1 and 7), are for illustrative purposes only denoting the appearance of any removable graphic images that may be applied to the plurality of plates and do not form part of the claimed design. The tripartite dashed lines on the plates (FIG. 7), constitute shading denoting transparency. The dashed lines on the theater box reflect surface shading denoting solid matter. The broken lines appearing in a zig-zag fashion on the front sidewalls of the theater box and along the front upper edge of the theater (FIGS. 1 and 2), are for illustrative purposes only denoting the appearance of any decorative images that may be placed on the theater box and do not particularly form part of the claimed design.
